UNITED STATES PATENT OFFICE.

WILLIAM I. BUNKER, OF LA GRANGE, ILLINOIS.

DESIGN FOR A BICYCLE-SADDLE.

SPECIFICATION forming part of Design No. 24,964, dated December 10, 1895.

Application filed November 12, 1895. Serial No. 568,744. Term of patent 14 years.

To all whom it may concern:

Be it known that I, WILLIAM I. BUNKER, a citizen of the United States, residing at La Grange, Cook county, Illinois, have invented 5 and produced a new and original Design for Bicycle-Saddles, of which the following is a specification, reference being had to the accompanying drawings, forming a part hereof.

In the accompanying drawings, Figure 1 10 represents a plan view of my design looking at it from the top, and Fig. 2 a transverse section taken on the line 2 of Fig. 1.

The leading feature of my design consists in the body portion for a saddle formed some-

what in the shape of a cone, so as to resemble when viewed in plan view, as shown in Fig. 1 of the drawings, an outline resembling a funnel.

A is the body portion. In a sectional view, B is the supporting-frame, b the sustaining- 20 socket and b' a securing set-screw.

What I claim is—

The design for a bicycle saddle as herein shown and described.

WILLIAM I. BUNKER.
